UNITED STATES PATENT OFFICE.

PHILIP ZALKIND, OF NEW YORK, N. Y.

GLUE ROLL.

1,421,654.

Specification of Letters Patent. Patented July 4, 1922.

Application filed July 8, 1920. Serial No. 394,694.

To all whom it may concern:

Be it known that I, PHILIP ZALKIND, a citizen of the United States, residing in the borough of Manhattan, city, county, and 5 State of New York, have invented an Improvement in Glue Rolls, of which the following is a specification.

This invention relates to an improvement in glue rolls and more particularly to glue 10 rolls employed in conjunction with boxing machines designed to fold and seal paper boxes, cartons and various forms of receptacles. As ordinarily made and sealed it is necessary, in acquiring access to the contents 15 of the form of paper box generally used for cereals and other similar merchandise for example, to disrupt the box in at least some portion thereof, and in the formation of which the ordinary type of glue roller answers the 20 purpose of applying the adhesive in the sealing of the box or package. Heretofore, however, various means have been suggested in the use of paper boxes and other forms of receptacles for making an opening in a pre- 25 determined portion of a box or receptacle for removing the contents thereof. In some of these forms of providing the opening in the box or receptacle predetermined portions 30 of the body of the box, and in some instances also predetermined portions of the covers or flaps forming the covers, are de- 35 signed to assume a normal position and condition in the box or receptacle and to be separated along predetermined lines to form 40 a tongue which may be removed partially from the flaps and partially from the body of the receptacle to form an opening to gain 45 access to the contents of the box and to be closed and maintained in position so that 50 portions of the contents of the box or receptacle may be removed from time to time and the remaining portion of the contents kept 55 in the box or receptacle under substantially the same conditions as regards the atmos- 60 phere and otherwise as when originally packed. Difficulty, however, has been ex- 65 perienced with this form of box or receptacle in sealing the same with the usual type of folding and sealing apparatus because of 70 the necessity of omitting the glue or other adhesive at predetermined portions of the flaps which form parts of the tongue that is 75 severed from the body of the box to form the opening therein, and my present invention 80 relates to a form of glue roll adapted to over- 85 come this difficulty.

In carrying out the invention the ordinary form of glue roll may be employed and associated in the usual manner with the glue pot or other vessel holding the adhesive and 60 from which to the surface of the glue roll the adhesive may be supplied in any usual or desired manner. In the surface of the glue roll, I provide an opening in which there is a movable member or plunger, the outer surface of which is preferably made to conform 65 with the surface of the roller and is normally in registry therewith so that the roller surface is continuous, this being the case when the adhesive is applied to the surface 70 of the roller. I also employ means operative at predetermined times in the revolution of the roller for shifting the plunger for instance for withdrawing the movable member or plunger into the roll so that when this portion of the roll is applied to the flap or 75 cover or other portion of a box no adhesive will be applied thereto, whereby, as will be understood, by suitably shaping the opening or openings in the roll and utilizing the same 80 in the proper positions and in the required number the adhesive may be omitted from those portions of the box or receptacle in sealing the same in which no adhesive is necessary so that the tongue portion of the 85 receptacle employed for making the aperture therein in all parts of the same may be free for use when the opening is to be made therein.

In the drawing:

Fig. 1 is a transverse section illustrating a glue roll embodying my invention.

Fig. 2 is a similar view showing the parts in the opposite position.

Fig. 3 is a plan view of a glue roll in which my improvement is embodied, and

Fig. 4 is a transverse section showing a modified form of the invention as is included in Fig. 3.

Referring to the drawing, the glue roll is 100 indicated at 10 and preferably comprises a hollow cylindrical member made of metal or any other suitable material. As illustrated in Fig. 3, the glue roll at the ends thereof is provided with collars 11 and 12 by which the glue roll is mounted on a shaft 13, preferably a stationary shaft, while at least one of the collars that is indicated at 11 is fitted with a sprocket 14 connected by a drive chain or otherwise to a suitable source of power by 105 which the glue roll is made to revolve, it being understood that the glue roll is asso-

iated with a glue pot or other adhesive receptacle in such a manner that the adhesive is applied to the surface of the glue roll in the turning of the roll.

- 5 In a suitable position in the glue roll, I provide the same with an opening 15. In this opening there is fitted a plunger 16. The plunger 16 is either connected to or made integral with a ring member which 10 may be made in parts, one part of which is indicated at 17 and the other part at 18. The inner surface of the ring member 18 is provided with a cam face 19, while the remainder of this inner surface of the ring member 18 is circular as is also the entire inner surface 20 of the ring member 17. These parts of the ring member may be connected by suitable bolts 22 passed through flanges on the parts of the ring member as 15 indicated at 21. Also as illustrated in Figs. 1 and 2, the part 18 of the ring member is provided with a guide pin 23 fitting into a socket 24 provided therefor on the inner face of the roll and fitted with a spring 25 which 20 extends between the inner surface of the roll and the adjacent face of the part 18 of the ring member. In this form of the invention, the shaft 13 is provided with a projection 26 lying within the ring member and 25 at its extremity fitted with a cam roller 27 adapted to contact with the cam face 19 in order to move the ring member and plunger at predetermined times in the revolution of the glue roll. As shown in Figs. 1 and 2, 30 the part 17 of the ring member may be fitted with adjusting screws 28 mounted in shoulders 29 thereon and adapted to engage with a reinforced portion of the glue roll as indicated at 30 to insure the proper registry 35 between the face of the plunger member and the surface of the glue roll.

- In the operation of this apparatus, as will be understood, the surface of the plunger member is normally in that position in which it registers with the face of the glue roll so that the same form a continuous surface. This is illustrated in Fig. 2 and in this position the surface of the glue roll has the glue or other adhesive applied thereto by passing through the glue pot or in any other manner. In the other position of the glue roll or that shown in Fig. 1, the cam roller 27 has passed a predetermined distance along the cam face 19 and in doing so, as will be understood, has withdrawn the ring member and the plunger a predetermined distance into the glue roll against the action of the spring 25. This, as will be furthermore understood, leaves a surface of predetermined configuration conforming to the outline of the opening in the glue roll at which no adhesive will be applied to the cover or flaps or other parts of a paper box or other receptacle in the operation of applying the adhesive, folding the parts and sealing the

same. When the glue roll is turned sufficiently far to permit the cam roller 27 to pass off the face of the cam 19 the spring 25 will force the ring member and the plunger to their normal positions so that the adjusting screws 28 abut against the reinforced wall 30 and the face of the plunger is again coincident with the surface of the glue roll.

In the form of the invention shown in Fig. 4, the glue roll and the plunger are substantially the same as those shown in the other forms of the invention. In this form of the invention I also employ a ring member 31 having a cam face as well as a projection secured to the fixed shaft and a cam roller mounted therein to engage with the cam face to move the plunger into the roller at predetermined times in the revolution of the glue roll. The cam face which corresponds to the cam face 19 is indicated at 32 while the projection which corresponds to the projection 26 is indicated at 33 and the cam roller 34 is the equivalent of the cam roller 27. Associated with this ring member 31 and either made integral with or connected thereto and parallel therewith is another ring member having a cam face 36 which is the complement of the cam face 32, and on the fixed shaft 13 I employ a cam 37 adapted to cooperate with the cam face 36 so that in the revolution of the glue roll the cam 37 is normally in contact with the cam face 36 to maintain the ring members and the plunger in that position in which the face of the plunger is coincident with the surface of the glue roll. In predetermined position of the glue roll, however, in the revolution thereof, the cam 37 runs off the cam face 36 and simultaneously the cam 105 roller 34 runs onto the cam face 32, whereby the plunger and cam rings will be drawn into the glue roll to the position indicated in Fig. 4, and after the cam roller 34 has run off the cam face 32 the cam 37 again engages 110 the cam face 36 so as to return the ring members and the plunger to their normal positions in which, as hereinbefore stated, the face of the plunger registers with the surface of the glue roll. In this construction 115 of the cam members, as will be understood, the use of the guide pin 32 and its socket, together with the spring for returning and normally maintaining the ring members and plunger in an initial position, may be dispensed with as the cam 37 cooperating with the cam face 36 on one of the ring members answers the same purpose.

While I have herein shown and described my present invention as used for applying 125 the adhesive to the flap ends of a paper box or carton for sealing the same in such a manner as to preclude the application of the adhesive to predetermined portions of the flaps, it will be understood that the use of the in- 130

vention is not in any sense of the word limited to this specific purpose, as it may be employed in various manners and for many purposes. It will also be understood that 5 while I have herein shown and described the invention as embodied in a glue roll together with mechanism for normally maintaining the face of the plunger in registry with the surface of the glue roll and with drawing the plunger so as to depress the face of the same at predetermined times in the revolution of the glue roll, the invention is not limited to this particular movement or mechanism for effecting the same.

10 15 I claim as my invention:

1. In an apparatus of the class described, a stationary shaft, a cylinder mounted to revolve on the said shaft and having an opening therein, a plunger fitting the opening in 20 the cylinder, a cam connected with the said plunger, means for normally maintaining the cam and plunger in such a position that the face of the plunger conforms to the surface of the cylinder, and a cam connected to 25 the said shaft and adapted at predetermined times in the revolution of the cylinder to engage the aforesaid cam to move the same and the plunger to cause the face of the plunger to assume a position beneath the surface of 30 the cylinder.

2. In an apparatus of the class described, a stationary shaft, a cylinder mounted to

turn on the said shaft and having an opening therein, a plunger movable in the said opening, a cam surrounding the said shaft 35 and connected to the said plunger, means for resiliently maintaining the said cam and plunger in such a position that the face of the plunger is in conformity with the surface of the cylinder, and a cam wheel carried by the said shaft and adapted at a predetermined time in the revolution of the cylinder to engage the said cam to move the same and the plunger to a position in which the face of the plunger lies below the surface of the cylinder. 40 45

3. In an apparatus of the class described, a stationary shaft, a cylinder mounted to turn on the shaft and having an opening therein, a plunger fitting the opening in 50 the cylinder, a cam surrounding the said shaft and connected to the said plunger, a cam wheel carried by the said shaft, a pin connected to the said cam, a socket member carried by the said cylinder and adapted to receive the pin connected to the cam, and a spring coacting between the cylinder and the cam in conjunction with the pin and socket to normally maintain the plunger and cam in a position in which the face of the 55 60 plunger is in conformity with the surface of the cylinder.

Signed by me this 29th day of June, 1920.
PHILIP ZALKIND.
